UNITED STATES PATENT OFFICE

WESLEY C. DARBY, OF DES MOINES, IOWA

ANTITHUMB SUCKING DEVICE

Application filed May 20, 1929. Serial No. 364,468.

The object of my invention is to provide an anti-thumb sucking device of simple, durable and inexpensive construction.

More particularly, it is my object to provide an anti-thumb sucking device which can be easily and conveniently placed on the thumb or finger of a child and will function to prevent the child from sucking the thumb.

With these and other objects in view, my invention consists in the construction, arrangement and combination of the various parts of my anti-thumb sucking device, whereby the objects contemplated are attained, as hereinafter more fully set forth, 15 pointed out in my claim, and illustrated in the accompanying drawings, in which:

Figure 1 shows a plan view of a hand equipped with an anti-thumb sucking device embodying my invention.

20 Figure 2 is a perspective view of the device omitting the tape or means for fastening it to the thumb.

Figure 3 is a diagrammatic view showing the normal condition of the arch of the mouth.

25 Figure 4 is a similar view illustrating the high arch and narrowed nasal passages resulting from thumb sucking.

Figure 5 illustrates the manner in which the child seals the lips to the thumb in sucking that member.

30 Figure 6 illustrates the device on the thumb and shows its relations to the parts of the mouth, whereby any sealing is prevented.

Figure 7 is a detail, sectional view of the 35 anti-thumb sucking device taken on the line 7—7 of Figure 6; and

Figure 8 is a similar sectional view showing the thumb in position against the side of the mouth and showing my device on the thumb functioning to engage the gum of the mouth to prevent sealing of the lips.

In the accompanying drawings, I have used the reference numeral 10 to indicate the hand 40 of an infant.

My anti-thumb sucking device A consists of a central bar 12, end bars 14 and side bars 16 spaced from and parallel with the central bar 12.

45 A plurality of lugs 18 are formed on the

central bar 12 and one of the end bars 14 is provided with lug-like extensions 20.

The anti-thumb sucking device A is adapted to be positioned on the thumb 22 of the hand 10 in the position shown, with the lugs 18 projecting inwardly relative to the palm of the hand.

It is adapted to be secured in position by means of a strip of adhesive tape 24 as best shown in Figure 7 of the drawings. An additional piece of adhesive tape 26 may be provided with the adhesive side outward to further facilitate a good connection between the device A and the thumb 22.

50 The adhesive tape 24, of course, has the adhesive side thereof inwardly or against the thumb 22.

55 I have briefly described my device and its application to the thumb of an infant and will now describe the harm done by thumb sucking and how my device operates to prevent some thumb sucking and consequently the resultant harm therefrom.

60 Referring to Figure 3, a cross section of the normal mouth and nasal pasageways is illustrated. The bottom of the mouth is indicated at 28 and the roof thereof at 30. The lower and upper rows of teeth are indicated at 32 and 34 respectively. Above the roof of the mouth, the nasal pasageways are indicated at 36. These pasageways are of rather complex shape as clearly shown in Figure 3.

65 Referring to Figure 5, it will be seen how an infant having the thumb sucking habit inserts the thumb 22 in the mouth and presses 85 against the roof 30 thereof. This pressure causes an upward arch of the roof 30, as clearly shown in Figure 4, which presses up on the bottom surfaces of the nasal pasageways 86 thereby constricting them. This effect in 90 itself is not quite as harmful as the combination of the upward pressure of the thumb on the roof 30 of the mouth and a vacuum created in the mouth by a sucking action. This sucking action is possible due to the lips 38 and 40 of the infant being pressed against the thumb and making an air-tight seal there-around. Because of the vacuum thus formed within the mouth, the normal atmospheric pressure outside of the face presses down on 95

the turbinate bones (not illustrated) above the nasal passageways 36 as indicated by the arrows 42 and further causes constriction of the passageways as clearly shown in Figure 4.

The harm done by such construction is due to the fact that the passageways 36 are so small that breathing is hindered, and the child thus afflicted is much more susceptible 10 to colds, because of the germs getting into the constricted passageways and being impossible to readily remove. Sometimes it is impossible to remove them at all and a turbinate bone operation must be performed.

15 The primary object of my invention is to provide a device which will effectively prevent the formation of a vacuum. This is possible as shown in Figure 6 due to the fact that the upper lip 40 which being pressed downwardly against the anti-thumb sucking device A can not enter in between the lugs 18 sufficient to cause an air-tight seal.

In other words, the lip 40 is too thick to enter between the closely spaced projections 25 or lugs 18 and air can enter the mouth between the lugs as shown by the arrow 44.

I have found that when an infant can not 30 create a vacuum within the mouth when sucking the thumb, the pleasure of sucking the thumb is eliminated and after two or three days and sometimes in a shorter period of time, he completely stops the habit.

The lugs 18 effectively prevent the formation 35 of an air seal around the thumb when the thumb is thrust in the mouth as clearly illustrated in Figures 5 and 6.

It is possible, however, to turn the thumb 40 sidewise and engage the corner of the mouth 46 with the lugs 18 and the corner of the mouth, being sharp, could enter between the lugs 18 and form an effectual seal, if it were not for the extensions 20, which are provided 45 to engage the gums adjacent the teeth 32 and 34 as shown in Figure 8. This section of the mouth is illustrated looking inwardly and the nail 48 of the thumb may be seen.

In the event that the infant then moves 50 the thumb away from the corner of the mouth to prevent engagement of the extension lugs 20 with the gums, as shown, the device A will be so far removed from the corner of the mouth that he can not get the corner 46 in between the lugs 18 and consequently can not 55 form an air seal.

55 In the event that the infant has the habit of sucking some finger rather than the thumb, the device can be applied to such finger with equal effectiveness to prevent the formation of an air seal.

Some changes may be made in the arrangement 60 and construction of the various parts of my anti-thumb sucking device without departing from the real spirit and purpose of my invention, and it is my intention to cover 65 by my claim, any modified forms of structure

or use of mechanical equivalents, which may be reasonably included within their scope.

I claim as my invention:

In a device of the class described, three substantially parallel bar members, end members connecting the ends of said bar members and curved to fit the inside of the thumb of a child for maintaining the device close to the hand, the center bar having outwardly projecting lugs and one end bar having projecting lug-like extensions 20, the side bars being adapted to be engaged by adhesive tape or the like for fastening the device on the thumb.

Des Moines, Iowa, March 12, 1929.
